SHUTTLE

Thomas Murphy, Schoolfield, Va.

Application March 15, 1938, Serial No. 196,067

3 Claims. (Cl. 139—217)

This invention relates to automatically threading loom shuttles and is more particularly directed to thread tensioning devices therefor.

It has been heretofore proposed to associate 5 resilient thread tensioning devices with the threading eyes of automatically threading shuttles, but the devices heretofore proposed for this purpose have not performed satisfactorily in practice; brushes, felt pads and the like have 10 therefore been more commonly employed to provide the necessary tension. It is found, however, that the tension cannot be maintained constant by such expedients and as the result of the uneven application of tension to the thread, 15 breakage commonly occurs as frequently as several times in an hour, with resultant interruption and delay in the operation of the machine.

It is an object of the present invention to overcome these difficulties and to provide a tensioning device which will maintain substantially 20 constant tension under varying operating conditions and with different grades of thread or yarn, and which will facilitate rather than impede the automatic feeding of the thread into 25 the thread passage of the conventional shuttle eye, thereby minimizing thread breakage and materially reducing the amount of attention and supervision required for satisfactory operation of the loom.

30 It is a feature of the invention that when the thread is overloaded, for example in taking up the slack during the feeding in of a new thread, the device is capable of yielding so as to promptly reduce the tension, thereby automatically preventing thread breakage.

35 A further object of the invention is the provision of a thread tensioning device which is simple and inexpensive to construct, which will not cut or wear the thread, and which may be 40 readily applied to conventional types of shuttle eyes without substantial modification thereof.

More specifically, the invention contemplates 45 the provision, in a shuttle eye for loom shuttles, of a tensioning device including a spherical element and a cup-shaped seat therefor, the seat being yieldingly urged into engagement with the spherical element so that the thread may be guided therebetween and sufficiently retarded thereby to afford the desired degree of tension. 50 The seat and the yielding means associated therewith are preferably disposed beneath the spherical element so that the feeding of the thread into the shuttle eye in the conventional manner is not interfered. Again, the thread, normally 55 tending to move downwardly in the eye when

excessive tension is applied thereto, may depress the seat against the action of the yielding means to momentarily relieve such excessive tension.

Further objects and features of the invention will be apparent from the following description 5 taken in connection with the accompanying drawing, in which:

Figure 1 is a plan view of one end of a loom shuttle illustrating the application of the invention thereto; 10

Figures 2 and 3 are side and end elevations respectively of the shuttle eye shown in Figure 1;

Figure 4 is a longitudinal sectional view of the 15 shuttle eye;

Figure 5 is a bottom plan view of the shuttle eye;

Figure 6 is a sectional view on an enlarged scale, taken substantially on the line 6—6 of 20 Figure 4; and

Figure 7 is an exploded view of the several 25 cooperating elements of the tensioning device illustrated in the preceding figures.

In order to facilitate an understanding of the 30 invention, reference is made herein to the embodiment thereof illustrated in the accompanying drawing and specific language is used to describe the same. It will nevertheless be understood that no limitation of the scope of the invention is thereby intended, various further 35 modifications and alterations of the illustrated embodiment being contemplated such as would normally occur to one skilled in the art to which the invention relates.

In Figure 1 of the drawing is shown the forward end of a loom shuttle 10, it being understood that the shuttle is provided with conventional means for supporting therein a bobbin 11 on which the thread 12 is wound. As the thread leaves the forward end of the bobbin, it is drawn 40 through a thread passage 13 extending longitudinally of the threading eye 14, and thence passes about guide pins 17 and 18, mounted in the threading eye, emerging finally from the 45 thread delivery opening 15 in the side of the shuttle. The threading block is provided with forwardly directed portions 20 and 21 and a downwardly directed horn 22 which are so shaped and positioned that on the first pick of the shuttle following replenishment, the thread is drawn 50 downwardly between the projecting portions 20 and 21 and past the horn 22 into engagement with the guide pins 17 and 18, in which position it is shown in Figure 1. It will be observed 55 that both the forward face of the horn 22 and

the pin 17 are inclined downwardly and rearwardly so that the thread tends to move toward and remain in the bottom of the thread passage 13.

5 The structure thus far described is conventional and the details thereof form no part of the instant invention. It will, therefore, be appreciated that the elements of this structure are not claimed herein except to the extent that 10 they enter into combination with the elements of the tensioning device and cooperate therewith to achieve the desired result. The application of the invention to other types of loom shuttles and threading eyes in the manner proposed herein is contemplated as a part of the present invention.

As shown more particularly in Figures 2, 4, and 6, a transverse opening 26 is formed in the shuttle eye 14 so as to extend therethrough and to intersect with the thread passage 13. As shown in Figure 2, the opening 26 is of generally rectangular shape as viewed in elevation, but is preferably rounded at its upper side. Received within the opening 26 is a seat 27 which is shaped 20 so as to conform generally in elevation to the configuration of the opening, being of less depth than the opening, and so dimensioned as to slide freely in the latter in a vertical direction.

25 A generally parti-spherical recess 30 is formed in the upper side of the seat 27 to receive therein with a loose fit a spherical element 31. A coil spring 33 engages the lower face of the seat 27 and is placed under compression by a set screw 34 threaded in an opening 35 in the lower portion 30 of the threading eye, the screw 34 being recessed to receive and support the spring 33 and being provided in its outer end with a kerf 36, by means of which it can be readily turned to adjust the degree of compression of the spring. 40 By the action of the spring 33, the seat 27 and the cooperating spherical element 31 are thrust upwardly, the latter being thereby seated at its upper side against the walls of the threading eye 14 which define the thread passage 13 at the 45 upper side of the opening 26, the said walls being preferably slightly rounded at this point to definitely position and properly receive the spherical element 31.

50 The mode of operation of the tensioning device will be apparent from the drawing and the foregoing description. Thus, during the threading operation, as the thread moves downwardly in the passage 13, it engages with and slightly depresses the spherical element 31, and moves about the same toward and into a position between the lower side of the spherical element and the bottom of the recess 30, in which position it is shown more particularly in Figures 4 and 6 of the drawing. The thread is now lightly clamped between the spherical element 31 and the seat 27 with a pressure determined by the adjustment of the screw 34, and constant tension is thereby applied to the thread as it is drawn off the bobbin 11, through the thread passage 13, and out at the thread delivery opening 15. During operation of the loom, the spherical element 31 frequently rotates or shifts its position, and to this no doubt is attributable, at least in part, the smoothness of operation of the tensioning device. Again, if excessive tension or a sudden jerk is applied to the thread, for example on the first pick of the shuttle following replenishment, the seat 27 is permitted to yield downwardly against

the action of the spring 33, which downward movement immediately relieves the strain on the thread and prevents breakage, attention being directed in this connection to Figure 4 in which is shown the position which the thread normally occupies.

5 The seat 27 and the spherical element 31 are preferably formed of hardened metal, but may be made of other suitable wear-resistant and smoothly finished material, such as porcelain, glass, or the like.

10 The simplicity of the device described herein and the ease with which it may be applied to existing conventional types of shuttle eyes will be readily appreciated. Thus, the device need include only the four small elements shown in Figure 7 and may be incorporated in any ordinary form of automatically threading shuttle eye by no modification of the latter other than the formation therein of the transverse opening 26 and the threaded opening for the reception of the screw 34. It has been found possible to secure, by this slight modification of existing types of shuttle eye, a reduction of the frequency of thread breakage from an average of several times 15 an hour to an average of once in seven or eight hours.

Having thus described the invention, what is claimed as new and desired to be secured by Letters Patent is:

1. In an automatically threading shuttle eye having a thread passage and means to direct a thread downwardly into said passage following replenishment, the combination with relatively displaceable cooperating thread engaging elements associated with said passage, of means located beneath the lower of said elements for yieldingly urging the same upwardly and toward the other of said elements to frictionally grip the thread therebetween, the other of said elements comprising a freely floating spherical member.

2. In an automatically threading shuttle eye having a thread passage and means to direct a thread downwardly into said passage following replenishment, the combination with relatively displaceable cooperating thread engaging elements associated with said passage, of means located beneath the lower of said elements for yieldingly urging the same upwardly and toward the other of said elements to frictionally grip the thread therebetween, the upper of said elements being of spherical shape and the lower of said elements having a concave surface partially embracing said upper element.

3. In an automatically threading shuttle eye having a thread passage and means to direct a thread downwardly into said passage following replenishment, the combination with relatively displaceable cooperating thread engaging elements associated with said passage, of means located beneath the lower of said elements for yieldingly urging the same upwardly and toward the other of said elements to frictionally grip the thread therebetween, the upper of said elements being of spherical shape and the lower of said elements having a concave surface partially embracing said upper element, said eye being so formed that the thread, when tensioned, extends away from said elements in a generally downward direction, whereby the lower of said elements may yield downwardly to relieve 70 excessive tension on the thread.

THOMAS MURPHY.
